UNITED STATES PATENT OFFICE.

ALEXANDER DOM, OF CINCINNATI, OHIO, ASSIGNOR TO THE SAMUEL C. TATUM COMPANY, OF CINCINNATI, OHIO, A CORPORATION OF OHIO.

PERFORATOR.

1,150,179.

Specification of Letters Patent.

Patented Aug. 17, 1915.

Application filed January 2, 1915. Serial No. 21.

To all whom it may concern:

Be it known that I, ALEXANDER DOM, a citizen of the United States, and residing at 1415 Pullan avenue, Cincinnati, in the county of Hamilton and State of Ohio, have invented a new and useful Perforator, of which the following specification is a full disclosure.

The invention relates to an improvement in perforators and primarily to a hand operated type for desk use in perforating sheets of paper. As disclosed, it provides a perforator, very simple in construction, with a few number of parts, conveniently assembled, and of increased durability over others in the commercial field for similar purposes. In the style represented, the punch supporting members are integral with their supporting base for a definite punch spacing. Other styles for a selective punch spacing, having their punch containing heads adjustable, are comprehended and within the aspect of this invention, which is primarily directed to the devices for reciprocating the punch members and in the punch or its shank construction.

An object of the invention is to provide a punch operating shaft with a groove longitudinally therein meshing with a tooth formed within the shank of a punch member movable transversely to the axis of the shaft. Adjacent each side of the shaft engaging tooth of the punch member, I provide opposite flank surfaces, each having a radius approximately equal to the radius of the shaft, adapted alternately to shoulder upon the shaft circumference, resistingly to confine the punch movements.

A further object of the invention is to provide handle arms for the punch operating shaft, interlockingly registering with the shaft, to rigidly fix the arms thereto, by forming the shaft receiving apertures of each arm of an outline similar to the contour of the shaft, keying therewith at any point throughout its length.

Various other features and objects of the invention will be more fully set forth in the description of the accompanying drawings, forming a part of this specification, and in such drawings like characters of reference denote corresponding parts throughout the several views of which:

Figure 1 is a top plan view of the perfo-

rator. Fig. 2 is a section on line 2—2, Fig. 55 1. Fig. 3 is a section on line 3—3, Fig. 1.

The perforator as illustrated provides a base 1, and two punch supporting heads 2, 3, cast integral with the base 1, but such construction is only incident to a particular style, it being obvious that the invention herein is applicable in any form of head construction or its method of mounting. The heads and their base may also be made of sheet metal stampings instead of cast material. Each head has its lower portion elongated forwardly and slightly raised from the upper surface of the base terminating with the slot 4, cut into the head as a paper receiving throat beneath the punch members. The gage of the slot is usually of a degree within a safe capacity that the parts of the device will withstand. The throat divides the punch and die elements or members of the perforator, the die herein being represented by an orifice 5 in the base, in registry with the movable punch member mounted in the head. The die, however, may be in the nature of an insert, removably secured in position and of various design of perforating outline. The circular form herein illustrated is of the most common demand for this type of perforator. Each punch 6 has an enlarged diameter shank portion 7 sliding within a corresponding diameter bore in the punch bearing 2. Such difference in the punch diameter provides a recess at the base of said bearing bore to receive a spring which engages against the shoulder at the end of the shank portion 7 for urging the punch to its normal position. The shank 7 of the punch is milled to provide a tooth 9, extending transversely to the punch axis with the clearance for the tooth flanks cut in arcs from the base of the tooth 95 toward the periphery of the shank and each preferably of a radius approximately equal to that of the rock shaft 10, which shaft journals in the heads normal to the punches. The shaft has a longitudinal groove 11 into which the tooth 9 meshes for reciprocating the punch with the rocking motion of the shaft.

A single tooth engagement with the shaft in the form shown enables the production of a large pitch of tooth and avoids shearing injury, as in cases wherein a plurality of fine pitch teeth are employed as rack and pinion. The coincidence of clearance arc and shaft

periphery provide stroke limits for the moving parts in either direction. This is relieving to the spring in a perforating stroke of the punch for the spring cannot be rigidly compressed, coil upon coil. Further, the clearance surface registers and engages with the periphery of the shaft under the wedge-like action to clampingly bind the shank within its bearing, and also shoulders 10 the upper portion of the shank upon the shaft relieving the tooth of excessive strains at the stroke limits. This is very advantageous and increases the life of the perforator and withstands the rough usage to which it 15 is frequently subjected. The single tooth connection presents quite an advantage in assembling the punches as no error can be made as to the relative alinement or plane of the punch ends.

20 The groove 11 is extended the entire length of the shaft, and while not absolutely essential in the type of perforator illustrated is of advantage in assembling the parts, for the shaft can be slid in one direction through one head to another of the series. The groove also provides a means 25 for rigidly connecting the handle arms 12, 12, to the shaft. The handle arms comprise sheet metal stampings bent into shape and joined at their free end by a stamping knob 30 13. The arms and knob can be made integral and bent into desirable shape. The ends of the arms connecting with the shaft are of circular outline and apertured to receive the shaft and provided with a lug 14, the lug engaging into the shaft groove to 35 key the lever or handle to the shaft.

The yoke form of handle is merely selective herein as of design enhancing value.

40 The shaft is provided with annular

grooves to receive the split rings 15, 15, for securely retaining the parts in position and offering convenient means for quickly assembling and dismantling the perforator.

Having described the invention, I claim:— 45

1. In a device of the class described, a base, bearings on said base relatively spaced, each provided with a throat slot, a shaft journaled in said bearings having a groove longitudinally therein, a punch member for 50 each bearing, each having an enlarged diameter shank movable within a bore of corresponding diameter in its bearing, said shank having a tooth formed therein meshing with said shaft groove and opposite 55 tooth clearance flanks, adapted to alternately shoulder upon said shaft and wedge-like engage the shank between the shaft and bearing to resistingly confine the punch movements, and a spring within said bearing bore for normalizing said punch member. 60

2. In a device of the class described, a base, bearing members relatively spaced on said base, a shaft journaled in said bearing members having a groove longitudinally therein, punch members movable within said bearing members transmittingly connecting with said shaft groove, and a lever apertured to receivingly coincide with said shaft 65 contour and thereby key into said shaft 70 groove for rigidly connecting said members.

In witness whereof, I hereunto subscribe my name, as attested by the two subscribing witnesses.

ALEXANDER DOM.
